UNITED STATES PATENT OFFICE

EDMUND C. MORGAN, OF NEW YORK, N. Y.; OLIVE EUGENIE MORGAN EXECUTRIX OF
SAID EDMUND C. MORGAN, DECEASED

COMBINED COAL MINING AND LOADING MACHINE

Application filed December 3, 1919, Serial No. 342,218. Renewed February 12, 1930.

My invention relates to improvements in combined coal mining and loading machines and the object of the improvement is to provide an efficient machine for the purpose. I 5 attain this object by the mechanism illustrated in the accompanying drawing, in which—

Fig. 1 is a plan view with the top protecting plate and a portion of the beams for supporting the plate broken away to enable the parts to be shown to better advantage;

Fig. 2 is a side elevation of the machine in which the top protecting plate and the supporting beams are shown in full;

Fig. 3 is a diagrammatical illustration to show adjustment of some of the parts;

Fig. 4 is an enlarged view of the rear portion of the machine, partly in elevation;

Fig. 5 is an enlarged sectional elevation of 20 the supporting framework;

Figs. 6 and 7 are enlarged elevations of the two upper superposed kerf-cutters at the forward end of the machine;

Fig. 8 is an enlarged sectional elevation of 25 the kerf-cutting mechanism and conveyer mechanism at the floor at the forward end of the machine;

Fig. 9 is an enlarged sectional elevation of a portion of Fig. 8;

30 Figs. 10 and 11 are detail views of the slack conveyer mechanism, Fig. 10 being a sectional plan view and Fig. 11 a sectional elevation;

Fig. 12 is an enlarged sectional elevation of 35 the mechanism for driving the floor kerf-cutter;

Fig. 13 is an enlarged sectional elevation of one of the adjustable elevated suspended kerf-cutters;

40 Fig. 14 is a plan view of one of the elevated suspended kerf-cutters;

Fig. 15 is a plan view of one of the coal breakers which is associated with each of the upper suspended kerf-cutters; and

45 Fig. 16 is a sectional elevation on the line 16—16 of Fig. 15 corresponding to the position indicated by the line 16'—16' of Fig. 1.

Similar numerals refer to similar parts throughout the several views.

50 Referring to Figures 1 and 2, 4 indicates

the main frame of the machine which is supported on the floor of the mine and adapted to be moved about by means of drive wheels 5 mounted on the axle 6 which is supported in suitable bearings in the main frame and may be arranged to be driven by suitable power means, such as an electric motor of a well known construction, and the idler wheels 7 mounted on axle 8 having bearings in the main frame arranged for vertical adjustment 55 so as to permit the tilting of the main frame with the axle 6 as the pivot.

9 indicates belts which may be mounted on the drive and idler wheels so as to provide the well known "caterpillar tread" where 60 the floor of the mine is of soft material, or to obtain better traction on a hard floor.

Vertically pivotally mounted on the forward projecting portion 10 of the main frame 4 is the frame 11 arranged to be revolved on 70 the main frame through an arc of 180° or more forwardly of the main frame and carrying kerf cutting means, coal breaking means and conveying means, the conveying means being arranged to discharge into a 75 hopper formed in the forward portion 10 of the main frame at any position of the travel of the main frame 11. The cutting mechanism carried on the frame 11 is designed to form a kerf at the floor of the mine chamber. 80

Mounted in the main frame 4 on two pairs of posts 12 and 13, which are arranged for vertical adjustment by power, is the framework comprising the beams 14 and 15, and the plate 16. Horizontally pivotally mounted 85 in the forward extending portion of the beams 14 and 15 by means of the pivots 17 and 18 is a ring 19. Mounted in the ring 19 to revolve through an arc of 180° or more extending forwardly from the main frame 4 is a 90 frame 20 which may be arranged to be revolved by power means. Carried in the frame 20 and extending outwardly therefrom is kerf cutting means 21, and a coal breaking means 22. This kerf cutting means is designed to form a kerf at the roof of the mine chamber. 95

Horizontally pivotally mounted on a frame 23 which is supported by the post 13 and arranged for vertical adjustment thereon is the 100

ring 24 which is similar to the ring 19 referred to above. Mounted in the ring 24 to revolve through an arc of 180° or more extending forwardly from the main frame 4 is 5 a frame 25 which may be arranged to revolve by power means. Carried in the frame 25 and extending outwardly therefrom is kerf cutting means 26 and a coal breaking means 27. This kerf cutting means is designed to cut 10 a kerf in the coal vein at some point intermediate the floor and roof kerf cutters as may be desired.

By referring to Figs. 4 and 5 placed end to end, the relation of the various parts of the 15 machine will become clearer. Fig. 5 shows at 4' a reinforcing cross-piece in the frame 4. A motor 105 is connected through worm gearing 106 to the axis 6 to drive the belt tractor shown at 9 in Fig. 2. Instead of having the 20 motor and winding drum 83 and 84 at the rear of the frame 4, it may be at 83' as shown in Fig. 5.

The roof jack 13 may be slotted at 100 so that the beams 14 and canopy 16 may be adjusted in elevation and secured in adjusted 25 position by the bolt and nut 101. A cross-piece 102 may be provided between the vertical roof jacks 13. The mechanism for operating the roof jacks is shown at 42, 43, 44, 30 45 in Fig. 2.

As shown in Fig. 8, a motor 107 may be connected through gearing 108 to the shaft 88' to drive the conveyor 28. The motor 89 as 35 shown in Fig. 1 is connected through the gearing 90 to a sprocket to drive the under-cutting kerf cutter 87.

As shown in Fig. 2, the under-cutting kerf cutter 87 is guided through a chute 39 which inclines upwardly to occupy an elevated position, and so as to deliver the cuttings from the 40 chute 39 to the receiver 38. As shown in Figs. 2 and 9, a motor 40 is mounted on a bracket 117 in position to rotate the shaft 40' which is journaled in the casing 38. As shown in 45 Fig. 10 the shaft 40' is connected to sprocket wheels for driving the bucket conveyor for taking the cuttings out of the receptacle 38 and delivering such cuttings directly to the conveyor 28, the forward horizontal portion 50 of which is within the boundary of the kerf cutter 87, as shown in Figs. 1 and 2.

The details of the slack conveyor mechanism may be varied as desired, but by way of example at what may be used, I have illustrated in Figs. 9 and 10 spaced apart sprocket 55 wheels 118 and 119, secured to the shaft 40'. Spaced-apart endless chains 120 and 121 are connected to the sprocket wheels and extended through suitable guideways 122. Connected 60 ed between the endless chains are a series of buckets 123 in position to scoop up the cuttings from the bottom of the receptacle 28 and deliver such cuttings to the conveyor 28.

In Figs. 6 and 7, I have shown enlarged 65 elevations of the forward roof kerf-cutter and

intermediate kerf-cutter. Fig. 6 shows an elevation of an expansible coal breaker 22 and the bracket 94 on which it is mounted. Fig. 7 shows the coal breaker detached from the support 95', which is shown in section.

Suitable conveyors 28, 29 and 30 are arranged in co-operative relation so as to convey the coal which is dislodged by the cutting means and breaking means described above to the rear of the machine where it may be dumped into the mine cars.

Where the coal vein has no objectionable material the cuttings from the two upper kerf cutting means 21 and 26 may be allowed to fall to the floor conveyor 28, but where dirty 80 bands, such as that indicated by 31, are encountered, the cuttings from either one or both of the upper kerf cutting means may be caught and carried away independently of the loading of the good coal as shown in the 85 illustration. The mechanism as shown is only designed to perform the separation of the cuttings from the kerf cutting means 26. This device consists of three conveyors 32, 33 and 34 arranged to co-operate to convey the cuttings of the undesired material from the kerf cutting means 26 to a car which may be placed at the side of the machine. The conveyors 33 and 34 are hung in the upper framework of the machine and are held stationary with respect to one another. The conveyor 32 is mounted in the frame 25 and arranged to discharge into the hopper of the conveyor 33, the center of which is located in line with the pivot of the frame 25 so that the conveyor 32 95 will discharge into the conveyor 33 at any position of the travel of the frame 25.

In order that the conveyor 32 may catch substantially all of the cuttings from the kerf cutting means 26 at varying depths of its cut in its travel, it is arranged for a horizontal movement on the frame 25 and is provided with a spring 35 to automatically keep the forward receiving end close to the face of the coal underneath the kerf cutting means 26. 110

The conveyor 28 may be driven by a separate electric motor indicated diagrammatically at 88. In a similar manner the conveyor 32 may be driven by a separate electric motor as 115 diagrammatically illustrated at 57 in Fig. 2. The conveyor 33 may be driven by an electric motor illustrated diagrammatically at 58. The conveyor 29 may be driven by an electric motor illustrated at 97 in Fig. 5 and shown 120 diagrammatically in Fig. 2. The loading conveyor 30 may be driven by an electric motor 69.

Where the weight of the machine is not sufficient to hold it stationary while a cut is being made, the posts 12 and 13 may be run up against the roof and in addition jacks 36 and 37 may be employed to press against the floor, thus firmly anchoring the machine against movement. In order to illustrate 125 the mechanism which can be used for mov-

ing the roof jacks 12 and 13 on both sides of the machine against the roof to anchor the main frame 4 during the mining operations, I have shown the roof jack 13 in Fig. 2 as provided with a rack 41 adapted to be engaged by suitable gearing 42 which is connected by worm gearing to a rod 43 extending diagonally downward toward the rear to another set of worm gearing 44 adapted to be operated by a motor 45. Preferably this motor is an electric motor and it will be seen that by connecting this motor by two sets of worm gearing to the rack 41 the roof jack 13 will be locked in position after the motor 45 stops. A similar electrically operated worm gear transmission may be located on the opposite side of the machine, as shown at 42', 43' and 44' in Fig. 1. It should also be understood that similar electrically operated worm gear transmissions may be applied to the roof jacks 12 on opposite sides of the machine.

In the operation of the machine as described above it will be seen that the several kerf cutting means may be made to travel in parallel planes or in planes at various angles one to the other. It will also be seen by the construction described that objectionable material can be separated from the coal in process of mining. It should be particularly noted that the plane of swinging feeding movement of each of the kerf cutters 21 and 26 always remains in fixed relation to the axis of swinging feeding movement of such cutters. For instance, the axis of swinging feeding movement of the cutter 21 is at the center of the ring 20 shown in Fig. 1. This axis is upright and at right angles to the plane of the kerf produced by the kerf cutter 21. The ring 20 fits within the outer ring 19 which is provided with trunnions at 17 and 18 for swinging movement on a lateral axis while supported by the longitudinal roof beams 14 and 15 which in turn are supported by the roof jacks 13.

Preferably a wide protecting plate 16 extends forward to a position adjacent the upper end of a mine wall so as to cover the protruding portion of the kerf cutter 21, as shown in Fig. 2. That is to say, the plate 16 supported on the spaced-apart beams 14 and 15 occupies a position close to the roof so as to cover substantially all of the operating parts of the machine and thereby protect the same against material which may fall from the roof. In order to adapt the beams 14 and 15 and the plate 16 mounted thereon to varying inclinations of the roof as compared with the floor, the beams 14 and 15 are pivotally mounted on the roof jacks 13, as indicated at 46 in Fig. 2.

As illustrated diagrammatically at 47 in Fig. 2 manual mechanism may be provided for tilting the ring 19 on its trunnions at 17 and 18 and thus tilt the kerf cutter 21 up

and down on a transverse horizontal axis. In order to drive the chain cutter a motor 48 is mounted within the ring 20 and geared, as shown by the dotted lines 49, to the chain cutter 21. This gearing is carried by the auxiliary frame 20'. It should be understood that the cutter frame, the auxiliary frame 20' and the ring 20 are all rigidly connected together and that the motor 48 is rigidly connected to this frame-work. The motor 48, 70 the ring 20, the auxiliary frame 20' and the kerf cutter 21 are therefore mounted to move bodily as a unit. In order to swing this unit on the center of the ring 20 as an axis a motor 50 is mounted on the frame 20' as shown in 80 Fig. 2, and geared at 51 to an inner annular gear on the bearing ring 19. After the latter has been adjusted by means of the wheel 47 on the trunnions 17 and 18 this ring 19 remains stationary. Therefore when the motor 50 is operated to drive the gearing 51 the kerf cutter 21 will be fed in an arc on an upright axis which is at the center of the ring 20 or of the ring 19. This axis may be inclined toward or away from the mine wall or be 90 vertical, but in any event the kerf cut by the kerf cutter 21 will be in a plane at right angles to such axis. If the inclination of the cutter were varied while the axis of feeding movement remained the same relative to the unmined mass the cutter would tend to move conically which would produce considerable cuttings and might cause the cutter to bind in the kerf which it was attempting to produce. By maintaining the axis of feeding movement at right angles to the plane of the kerf cutter, as shown in the drawings, there will be no tendency for conical feeding movement and the kerf will remain substantially of the same width and in the same plane throughout.

The kerf cutter 26 is also mounted for a swinging feeding movement on an upright axis which always remains at right angles to the plane of the kerf cutter. The ring 24 of Fig. 2 corresponds to the ring 19 of Fig. 1 and is also mounted in trunnions, as indicated at 52, so as to swing on a transverse horizontal axis. For this purpose a wheel 53 is mounted on the frame 23 in position to engage the ring 24 at its rear portion and tilt the same on the trunnions 52. The frame 25 corresponds to the frame 20' of Fig. 1 and carries the gearing for transmitting power from a motor corresponding to that shown at 48 in Fig. 1, to the chain cutter 26. A motor 54 is mounted on the frame 25 and provided with gearing 55 for securing swinging feeding movement of the frame 25 and the kerf cutter 26 on an upright axis which is at the center of the ring 24. The latter is adapted to receive a ring corresponding to that shown at 20 in Fig. 1, which is connected rigidly to the frame 25.

While the conveyer 32 is suspended by the

bracket 56 from beneath the frame 25 an electric motor 57 is adapted to operate the conveyer in its various positions relative to the kerf cutter 26. The conveyer 33 is adapted to be operated by a motor illustrated diagrammatically at 58. This conveyer 33 may be suspended from the beams 14, 15 and the frame 23 by means of links, as illustrated at 59, 60 and 61 in Fig. 2. The rear conveyer 34 is adapted to be suspended from the beams 14 and 15 by means of the links 62 and 63, and this conveyer is adapted to be operated by the motor illustrated diagrammatically at 64.

15 The rear conveyer 30 is provided with a main frame 65 and an auxiliary frame 66 pivoted at 67 to the frame 65. By means of the wheel 68 the rear section of the conveyer 30 may be swung on the axis 67 so as to adjust 20 the elevation of the delivery end of the conveyer. The conveyer 30 may be operated by a motor illustrated diagrammatically at 69.

25 A buffer may be provided at the lower rear central portion of the conveyer frame 65 in position to be engaged by the projecting coupling mechanism of a mine car. Such a buffer may comprise a cylindrical head 70 provided with a forwardly extending rod 71 extending through brackets 72 and 73 between which is located a spring 74. When a mine car 75 is moved along the mine track its forward coupling device 76 will engage the buffer and thus stop the mine car without shock or jar to the mining and loading 30 machine.

35 The mine car shown at 77 in Fig. 1 is located on a mine track 78, as shown in Fig. 1. Another mine track 79 is laid along the other side of the mine to receive an empty car as soon as the car 77 has been filled with foreign material. When the car 77 has been loaded the rear conveyer 34 may be readily swung into position for directing foreign material into a mine car on the track 79. It should 40 also be noted that when a car 75 on the central mine track 80 has been filled with coal the rear conveyer 30 may be swung on its upright axis 81, 82 so as to direct the coal into a mine car on either track 78 or the track 79. 45 It should be particularly noted that by swinging the kerf cutters the dislodging mechanism and the forward conveyer 28 through an angle of 180 degrees or more from one side of the mine chamber to the other a wide 50 entry is continuously being made so that not only the mine track 80 may be extended forward from time to time, but tracks 78 and 79 on both sides of the track 80 may be laid and extended forward from time to time in 55 accordance with the continuance of the mining operations.

55 In order to avoid the necessity of extending the track 80 at frequent intervals the mining and loading machine is provided 60 with the endless belt traction mechanism

illustrated at 9, 9 in the drawings. The mining machine may be propelled along the mine floor in advance of the track 80 a considerable distance before the track 80 need be extended forward. For instance, the track 80 may first 70 be laid up close to the rear end of frame 4 and then the mining and loading machine moved forward step by step in accordance with the mining operations until the mine car 75 could no longer be moved forward to 75 receive coal from the conveyor 30 without running off the track 80. At 83 I have diagrammatically illustrated a motor for operating rope-winding mechanism 84 for the rope sections illustrated at 85 in Fig. 2, these 80 rope sections being secured to the forward portion of the ring frame 86 on which is mounted the frame 11 carrying the lowermost kerf cutter or under cutter 87 and the conveyer 28. The latter is adapted to be operated by an electric motor illustrated diagrammatically at 88. The kerf cutter 87 is adapted to be driven by a motor 89 geared to the kerf cutter, as shown at 90 in Fig. 1. The frame 11 may be provided with a scoop 90 91 in position to scoop up the cuttings deposited on the mine floor by the emerging portion of the kerf cutter 87. The scoop 91 is adapted to discharge the cuttings into the chute 39 and thence onto the conveyer 38 95 which is adapted to be operated by an electric motor 40. The conveyer 38 may be L-shaped so as to have a vertical portion extending to the motor 40 and a horizontal portion beneath the opening of the chute 39, the 100 upper horizontal portion of the conveyer 38 being adapted to travel to a position above the conveyer 38, as shown in Fig. 1. It should also be noted that the kerf cutter 87 travels from the scoop 91 along the chute 39 105 so as to actually convey the cuttings along the chute and then up an incline so as to deposit such cuttings on top of the horizontal traveling portion to the conveyer 38.

110 While the motor 89 drives the kerf cutter 87 the latter, together with the conveyer 28, may be swung by means of the ropes 85 on the center of the ring 86 as an axis, concentrically with the circular shaped hopper 10 so that the conveyer 28 will be in delivery communication with this hopper throughout the range 115 of feeding movement of the cutter 87 from one mine wall to the other which is an angular movement of approximately 180 degrees.

120 It should also be noted that by means of the mechanism for tilting the frame 4 on the axle 6 as an axis the kerf cutter 87 may be tilted, together with its axis of swinging movement, so that the plane of the cutter will always be at right angles to such axis. 125 I have illustrated diagrammatically at 92 a screw-threaded rod mounted on the axle 8. A motor and worm gearing may be provided as illustrated at 93 in Fig. 2 to tilt the frame 4 on the axle 6 as an axis and thus change 130

the elevation and inclination of the under-cutting kerf cutter 87.

As fast as the cutting of the roof kerf, floor kerf, and intermediate kerf proceeds the material is broken down by means of the expandable breaking devices 22 and 27. These breaking devices are respectively mounted on frames 94 and 95. The frame 94 is rigidly connected to the auxiliary frame 20' and the frame 95 is rigidly connected to the frame 25. The breaking devices being thus in fixed relation to the frame which supports them the mechanism for operating such breaking devices may be mounted on such supporting frames to move bodily therewith. The breaking devices 22, for instance, may be operated by means of a hydraulic pump connected thereto by suitable piping connections mounted on the frame 94, the pump and the electric motor for operating the same being mounted on the frame 20' between the ring 19 and the rear end of the kerf cutter 21. In the same manner the hydraulic expandable breaking device 27 may be provided with suitable piping connections mounted on the frame 95 and leading to a hydraulic pump and an electric motor for operating the same both mounted on the frame 25 in advance of the ring 24. The breaking down of the coal need not be interfered with by the operation of removing the dirty band 31 between the upper and lower veins of coal because the kerf cutter 26 will remove this foreign material and the latter will be conveyed into a mine car 77 on the side track 78 while the coal is being dislodged by the breakers 22 and 27 and the coal is being conveyed to the mine car 75 by the conveyors 28, 29 and 30.

Having described my invention and the preferred mechanism embodying the same, I claim:

1. In a mining machine, the combination with a portable supporting frame, of a plurality of spaced-apart kerf-cutters, a plurality of cutter carrying frames one for each of said kerf-cutters mounted on said supporting frame in superposed co-operative relation to support said kerf-cutters for arcuate movement in the same general direction on approximately the same upright axis to cut kerfs in advance of a mining machine along an upright mine wall, means for adjusting the upright axis of feeding movement of each cutter carrying frame to bring the cutters into positions to cut either in superposed parallel planes or in planes intersecting each other along such upright mine wall in advance of said supporting frame, and means for operating said kerf-cutters so that each will cut in a plane at right angles to its upright axis of feeding movement.

2. In a machine of the class described a main frame tiltably mounted, a kerf cutter carrying frame pivotally mounted on said main frame to revolve in a fixed path with

respect to said main frame, a supplemental frame mounted on said main frame for vertical adjustment with respect thereto, a kerf cutter carrying frame pivotally mounted on said supplemental frame to revolve in the same general direction as the first mentioned kerf cutter carrying frame, and means for shifting the pivot of the said kerf cutter carrying frame at its support on said supplemental frame to permit it to revolve in planes at an angle to the plane of movement of the kerf cutter carrying frame mounted on the said main frame. 70

3. In a machine of the class described a main frame tiltably mounted, a kerf cutter carrying frame pivotally mounted on said main frame to revolve in a fixed path with respect to said main frame, a supplemental frame mounted on said main frame for vertical adjustment with respect thereto, a kerf cutter carrying frame pivotally mounted on said supplemental frame to revolve in the same general direction as the first mentioned kerf cutter carrying frame, and means for shifting the pivot of the said kerf cutter carrying frame at its support on said supplemental frame to permit it to revolve in planes at an angle to the plane of movement of the kerf cutter carrying frame mounted on the said main frame, a third kerf cutter carrying frame supported by said main frame and adjustable to travel in a plane parallel to the plane of travel of the other kerf cutter carrying frames or in a plane at an angle to the plane of travel of the other kerf cutter carrying frames. 80

4. In a mining and loading machine, the combination with a supporting frame, of mechanism mounted on said supporting frame in position to operate on an upright mine wall to automatically mine and load coal from its native bed, means mounted on said frame in position to automatically mine foreign material from a band in the coal vein intermediate the floor and the roof of the mine chamber without interfering with the separate operation of the mining and loading of the coal, and means mounted on said frame in position for separately loading such foreign material independently of the loading of the coal so as not to be mixed therewith while the coal is being mined and loaded. 105

5. In a mining and loading machine, the combination with a supporting frame, of mining and loading apparatus mounted on said supporting frame and comprising a kerf-cutter for cutting a kerf along the mine vein, an additional kerf-cutter mounted on said frame in position to cut foreign material from a dirty band in the coal vein spaced from the kerf cut by said first-named kerf-cutter, and conveying mechanism mounted on said frame in association with said additional kerf-cutter to convey the foreign material dislodged thereby to a separate loading 110 115 120 125 130 135

position so as not to mix with the mineral mined and loaded from the mine vein.

6. In a mining machine, the combination with a main frame, of anchoring mechanism adapted to engage the roof of the mine chamber to anchor said main frame in a predetermined position, an elongated flat canopy supported on said anchoring mechanism and movable therewith to a position at or near the 10 roof of the mine chamber to extend across the main frame, and kerf-cutting mechanism mounted at the forward portion of said canopy in position to cut a kerf in a mine wall in continuation of such roof.

15. 7. In a mining machine, the combination with a supporting frame adapted to extend in advance of the mine track adjacent an upright mine wall, of kerf-cutting mechanism mounted on said supporting frame to extend 20 in advance thereof in position to cut a kerf approximately in the plane of the floor of the mine chamber, additional kerf-cutting mechanism adjustably mounted on said supporting frame to cut a kerf approximately in 25 a plane of the roof of the mine chamber and above the floor kerf, intermediate kerf-cutting mechanism mounted on said supporting frame to extend in advance thereof in position to cut a kerf in a plane between the floor 30 and roof of the mine chamber, said kerf-cutting mechanisms being mounted on said frame in cooperative relation to each other to cut superposed kerfs in the mine wall in advance of said supporting frame, means individual to each of said kerf-cutting mechanisms to operate the same as separate independent units but cooperating with each other to cut such superposed kerfs in said 35 mine wall.

40. 8. A mining and loading machine comprising a supporting frame, coal mining mechanism mounted thereon and projecting in advance thereof in position for operation on an upright mine wall, supplemental mining mechanism mounted on said frame in position 45 to operate on such mine wall intermediate the floor and the roof of the mine chamber to remove foreign material from a dirty band in the mine vein, and conveyer mechanism 50 mounted on said frame in association with said supplemental mining mechanism in position to receive the foreign material dislodged thereby and convey such foreign material rearwardly along said supporting frame and 55 off to one side thereof.

9. In a mining machine, the combination with a supporting frame, of kerf-cutting mechanism mounted thereon to extend in advance thereof in position to operate on the 60 upright wall of a coal vein, supplemental kerf-cutting mechanism mounted on said frame in position to operate on such wall to cut a dirty band therefrom, and conveyer mechanism mounted on said frame in position 65 to receive the cuttings of foreign ma-

terial from said supplemental kerf-cutting mechanism and transfer such cuttings to a position extraneous to the machine.

10. In a mining machine, the combination with a portable supporting frame, of a plurality of superposed kerf-cutters mounted on the forward end of said frame each for a separate and individual feeding movement on an independent upright axis but arranged for cooperative relation for operation on an upright mine wall in advance of the mining machine and individual to each of said kerf-cutters for adjusting the inclination thereof for maintaining the plane of the swinging feeding movement at right angles to its line of feeding movement, and individual motors connected to the respective kerf-cutters to drive the latter and feeding the same at their adjusted inclination to cut superposed kerfs in an upright mine wall in advance of said supporting frame.

11. In a mining machine, the combination with a supporting frame, of a plane chain kerf-cutter, a ring pivoted to said frame for adjustment relative thereto on a horizontal transverse axis, a cutter carrying frame for said kerf-cutter, a circular extension on said cutter carrying frame fitting into a circular bearing in said ring, a motor on said extension connected to said kerf-cutter to drive the same, and a separate motor connected between said cutter carrying frame and said ring to swing the kerf-cutter concentrically of said ring.

12. In a mining machine, the combination with a frame, of an elongated plane chain kerf cutter mounted at one end of said frame, a circular extension at the other end of said frame, means comprising a motor on said frame for driving said kerf cutter, an annular bearing support for receiving said circular extension, means for supporting said circular extension for suspension below said annular bearing and power transmission mechanism comprising an additional motor for swinging said kerf cutter on an axis at right angles to the plane kerf cut by said cutter.

13. In a mining machine, the combination with a portable supporting frame adapted to move along a mine chamber to a position adjacent an upright working face at the heading of such mine chamber, of a plurality of plane chain kerf-cutters, means for mounting said chain kerf-cutters on said supporting frame in superposed co-operative relation in advance of said supporting frame to cut simultaneously spaced-apart plane kerfs across such heading, such mounting means comprising individual pivotal supports for said kerf-cutters for adjustments on superposed axes each extending transversely to the longitudinal length of the machine, and mechanism for individually adjusting the upright axes of swinging feeding movements of said plane kerf-cutters.

14. In a mining machine, the combination with a supporting frame, of a plurality of plane kerf-cutters adapted to operate on an upright mine wall, means for mounting said kerf-cutters on said supporting frame in superposed co-operative relation each to swing on an individual axis through an angle of 180 degrees or more from one side of the mine chamber to the other side thereof and in advance of the forward end of said supporting frame at such upright mine wall, and means individual to each kerf-cutter to adjust its inclination on a horizontal axis transverse to the longitudinal length of said supporting frame while maintaining its axis of swinging movement at right angles to the plane of the kerf cut by the corresponding kerf-cutter. 5 70
15. In a mining machine, the combination with a main frame, of a plurality of spaced-apart roof jacks thereon, a canopy supported by said roof jacks in position to span the space at the roof above said main frame, and kerf-cutting mechanism mounted in position to cut a kerf approximately in the plane of the roof in advance of said canopy. 10 75
16. In a mining machine, the combination with a main frame, of spaced-apart roof jacks mounted thereon, longitudinal spaced-apart beams respectively mounted on said roof jacks 20 80
- 25 and movable upwardly therewith to a position adjacent the roof and spanning the same above said main frame, and kerf-cutting mechanism carried by said beams in position to cut a kerf approximately in the plane of the 30 85
- 35 said roof. 90
17. In a mining machine, the combination with a main frame, of spaced-apart roof jacks, spaced-apart longitudinal beams respectively pivoted to said roof jacks and carried upwardly thereby, a plate carried by said beams in position to span said roof and engage the latter to support the same, and kerf-cutting mechanism mounted on said beams in position to cut a kerf in advance of 40 95
- 45 said plate approximately in the plane of the roof. 100
18. In a mining machine, the combination with a supporting frame, of roof-supporting mechanism comprising a plate spanning the roof above said supporting frame, and kerf-cutting mechanism supported by said roof-supporting mechanism in position to cut a kerf approximately in the plane of the 50 105
- 55 roof. 110
19. In a mining machine, the combination with a main frame, of a kerf-cutter carrying frame pivotally mounted on said main frame for arcuate adjustment on a horizontal transverse axis with respect to said main frame, a kerf-cutter pivoted to said kerf-cutter carrying frame for arcuate feeding movement laterally on an upright axis extending transversely of said horizontal axis, another kerf-cutter carrying frame spaced above the first- 60 115
- 65 named kerf-cutter carrying frame for loca- 120
- tion adjacent the roof, a supplemental frame mounted on said main frame for adjustment in elevation relatively thereto and pivotally carrying said second-named kerf-cutter carrying frame for adjustment on a horizontal transverse axis, and an additional kerf-cutter pivoted to said second-named kerf-cutter carrying frame for lateral feeding movement on an upright axis extending transversely of the horizontal pivotal axis of said second-named kerf-cutter carrying frame. 75
20. In a mining machine, the combination with a main frame, of a kerf-cutter mounted on said main frame to swing on an upright axis relatively thereto in position to cut a kerf at the floor level of the mine chamber, a supplemental frame mounted on said main frame for vertical adjustment relatively thereto, an additional kerf-cutter pivotally mounted on said supplemental frame for a laterally swinging movement on an upright axis, and an additional pivotal connection between said second-named kerf-cutter and said supplemental frame for adjustment of said second-named kerf-cutter on a horizontal transverse axis to cut in planes intersecting the plane of cut of the first-named kerf-cutter. 80 85
21. In a mining and loading machine, the combination with a supporting frame, of elongated mining mechanism mounted thereon to have a swinging feeding movement relatively thereto on an upright axis to prepare an upright mine wall for dislodging the material therefrom to provide extension of the mine chamber equal in width to two or more times the width of said supporting frame, means mounted on said frame in association with said mining mechanism to swing therewith on said upright axis in position to dislodge a stratum of foreign material while the coal is being mined, and means in position to receive such dislodged foreign material from the mine wall and convey it along said supporting frame to a mine car on a side track in the mine chamber. 90 95
22. In a mining machine, the combination with a supporting frame, of coal mining mechanism mounted thereon for swinging feeding movement through an angle of 180 degrees or more in advance of the forward end of said frame across an upright mine wall to provide for the extension of the mine chamber of approximately three times the width of said supporting frame, means on said frame 100 105
- 110 in position to mine a stratum of foreign material from such upright mine wall, and means on said frame in co-operative relation with said means for mining foreign material for loading the latter by transferring the same away from the mine wall along said frame to a mine car on a side track between one of the lateral mine walls of the mine chamber and said supporting frame. 115
23. In a mining machine, the combination 120
- 125 130

with a supporting frame adapted to travel on a mine track along the center of a mine chamber, of mining mechanism adapted to dislodge a crescent-shaped mass of coal from an upright mine wall in advance of the mine track and toward both sides of the end thereof, means on said frame in position to mine a stratum of foreign material from the mine vein and in such crescent-shaped mass, and loading mechanism on said frame in co-operative relation with said means for mining foreign material for transferring the latter from the mine wall along said frame into a mine car on a side track in said mine chamber.

15 24. In a mining and loading machine, the combination with supporting frame-work, of a chain kerf-cutter mounted thereon in position to cut a kerf in an elevated position, a conveyor adapted to receive cuttings from
20 said kerf-cutter, and means for holding the receiving end of said conveyor against the mine wall in position adjacent said kerf cutter to receive the cuttings while said kerf-cutter projects at varying distances into the
25 mine wall.

25 mine wall.
25. In a mining and loading machine, the combination with supporting frame-work, of a chain kerf cutter mounted thereon in position to cut a kerf in an elevated position, a
30 conveyer adapted to receive the cuttings from said kerf cutter, and means for yieldingly holding the receiving end of said conveyer against the mine wall in an elevated position adjacent said kerf cutter to receive the cut-
35 tings while said kerf cutter projects at varying distances into the mine wall.

26. In a mining and loading machine, the combination with supporting frame-work, of an elongated chain kerf cutter mounted thereon, a self-contained conveyer supported on said frame-work with its receiving end adjacent the emerging run of said chain kerf cutter to receive the cuttings therefrom, and a spring for yieldingly holding the receiving end of said conveyer against the mine wall in position to receive such cuttings while said kerf cutter extends at varying distances into the mine wall.

27. In a mining and loading machine, the
50 combination with a main frame, of a supplemental
frame pivotally connected to said
main frame for movement up and down on
a horizontal transverse axis, a chain kerf
cutter mounted on said supplemental frame,
55 a conveyer supported by said supplemental
frame with its receiving end in position to
collect the cuttings from said kerf cutter, and
means for yieldingly holding said conveyor
against the mine wall while said kerf cutter
60 projects varying distances into the mine wall.

60 projects varying distances from the main frame.
65 28. In a mining and loading machine, the combination with a main frame, of a kerf cutter, a supplemental frame for supporting said kerf cutter, means for supporting said supplemental frame on said main frame for

swinging feeding movement on an upright axis permanently at right angles to the plane of the kerf cut by said kerf cutter and for up and down tilting movements on a horizontal transverse axis, a conveyer mounted on said supplemental frame with its receiving end in position to receive the cuttings from said kerf cutter, and means between said supplemental frame and said conveyor for yieldingly holding the receiving end thereof against the mine wall while said kerf cutter projects varying distances into said mine wall.

29. In a mining and loading machine, the combination with a main frame, of means comprising spaced-apart endless belts at opposite sides of said main frame for supporting the latter, said supporting means also comprising spaced-apart wheels at opposite sides of said main frame, means associated with the axle of the forward wheels for tilting the main frame on the axis of the rear wheels, a traveling chain kerf cutter mounted on the forward end of said main frame to swing on an upright axis through an angle of 180° or more to cut a kerf approximately in the plane of the floor of the mine chamber, a conveyer having a receiving portion within the boundary of said kerf cutter, a hopper on the forward end of said frame and in delivery communication with the delivery end of said conveyer throughout its lateral movement, and an additional conveyer on said main frame with its receiving end in said hopper.

30. In a mining machine, the combination with a supporting frame, of mining mechanism mounted thereon, loading apparatus mounted on said frame for receiving material from said mining mechanism as dislodged and delivering the same to a mine car, a chain kerf-cutter mounted on said supporting frame in position for removing a band of foreign material from the mine vein, and supplemental loading apparatus mounted on said frame in association with said kerf-cutter for receiving dislodged foreign material and transferring the latter along said frame to a position separated from said mine car to secure separate loading of the mineral and foreign material from the working face of the mine vein. 100 105 110 115

31. In a mining machine, the combination with a supporting frame, of mining mechanism mounted thereon, loading apparatus mounted on said supporting frame in association with said mining mechanism, supplemental mining mechanism on said supporting frame in an elevated position for removing a band of foreign material from the mine vein substantially above the floor level, and supplemental loading apparatus mounted on said supporting frame in association with said supplemental mining mechanism in position to receive the dislodged foreign material and transfer the same along said support- 120
125
130

ing frame independently of said first-named loading apparatus to secure separate mining and loading of the foreign material from the same working face of the mine vein.

32. In a mining and loading machine, the combination with a supporting frame, of coal mining mechanism mounted thereon in position to operate on the upright working face of a coal vein, loading apparatus mounted on said frame in position to automatically receive the mined coal and convey it toward loading position, a traveling chain-cutter mounted on said frame in elevated position to remove a band of foreign material from such upright working face at the same time that said mining mechanism is operating, and additional loading apparatus mounted on said frame in elevated position adjacent said cutter to automatically receive the dislodged foreign material and transfer such foreign material along said frame for discharge at one side of said supporting frame so as not to mix with the said mined coal.

33. In a mining machine, the combination with a frame, of a chain cutter mounted thereon to travel in a horizontal plane along the cutting runs thereof and at an elevation along the return portion, a main conveyer mounted on said frame, a chute for directing the cuttings from the chain cutter to the elevated portion of its travel, and a supplemental conveyer at such elevated portion in position to receive the cuttings and deliver the same to said main conveyer.

34. In a mining machine, the combination with mining and loading apparatus comprising a kerf-cutter for cutting a kerf along the mine vein, of an additional elevated kerf-cutter for mining foreign material from the coal vein in a position elevated above the base of the mine wall, and means for separately loading such foreign material without interfering with the operation of said mining and loading apparatus.

35. In a mining machine, the combination with a supporting frame, of a plurality of mining mechanisms comprising kerf-cutters mounted on said frame in position to operate simultaneously on an upright coal wall in a mine chamber to cut spaced-apart kerfs each extending in a general horizontal direction, and a plurality of conveying devices associated respectively with said mining mechanisms to simultaneously convey the dislodged material to separate loading positions.

36. In a mining and loading machine, the combination with a supporting frame, of means mounted on said frame for mining coal in comparatively large pieces, means also mounted on said frame in position to mine foreign material from the body of the coal vein, and separate loading mechanisms each comprising a traveling conveyor having superposed positions traveling in opposite directions mounted on said frame one for load-

ing the mined coal and the other for loading the mined foreign material so as not to mix with the coal loaded.

37. In a mining machine, the combination with a chain kerf-cutter, of an endless traveling conveyor with its receiving end within the boundary of said chain kerf-cutter, a chute associated with said chain kerf-cutter to receive cuttings from the latter, and means for delivering such cuttings directly to the receiving end of said conveyor.

38. In a mining machine, the combination with a chain kerf-cutter, of a conveyor with its receiving end within the boundary of said chain kerf cutter, and means for collecting the cuttings from said kerf-cutter and delivering such cuttings on top of the receiving end of said conveyor.

39. In a mining machine, the combination with a cutter-frame, of an endless chain cutter mounted thereon, a conveyor having its receiving end within the boundary of said chain cutter, a chute for receiving cuttings from said chain cutter and directing such cuttings to an elevation, a receptacle for receiving said cuttings, and automatic coal-operating mechanism for taking such cuttings from said receptacle and delivering them to the receiving end of said conveyor.

40. In a mining and loading machine, the combination with a supporting frame, of cutting mechanism mounted thereon, a conveyer mounted on said frame in position to receive cuttings from said cutting mechanism, and means for holding the receiving end of said conveyer against the mine wall in a substantially elevated position to receive the cuttings while said cutting mechanism projects at varying distances into the mine wall.

41. In a mining machine, the combination with a supporting frame, of mining mechanism adapted to operate on an upright coal mine wall to prepare the same for dislodging the coal therefrom to provide extension of the mine chamber wider than the width of the said frame, loading apparatus for the dislodged coal, means for dislodging a stratum of foreign material while the coal is being mined, and means mounted on said frame in position to receive the foreign material and convey the same away from the mine wall so as not to be mixed with mined coal.

42. In a mining and loading machine, the combination with a supporting frame, of a kerf-cutter mounted thereon, and means for yieldingly holding the receiving end of said conveyer against the mine wall substantially above the base thereof in position to receive the cuttings while the kerf-cutter projects at varying distances into the mine wall.

43. In a mining machine, the combination with a supporting frame, of a plane chain kerf-cutter mounted thereon for adjustment relatively thereto on a horizontal transverse axis and on an upright axis means for oper-

ating said kerf-cutter, and a breaker connected to said kerf-cutter to always lie in the plane thereof irrespective of its adjustment on said axes and movable into the kerf cut by said kerf-cutter.

- 5 44. In a mining machine, the combination with a supporting frame, of a plane kerf-cutter, a pivotal support for adjustment of said kerf-cutter on a horizontal axis extending transversely of the longitudinal length of the 10 machine, another pivotal support for swinging feeding movement of said kerf-cutter on an upright axis always maintained at right angles to the plane of said kerf-cutter, and 15 a flat breaker mounted on said kerf-cutter to move bodily therewith into the kerf produced thereby to always lie in the plane of said kerf-cutter for operation in such kerf independently of the feed of said kerf-cutter.
- 20 45. In a mining machine, the combination with a main frame, of roof jack mechanism therefor, a canopy supported by said roof jack mechanism to span and cover the space at the roof above said main frame, and mining mechanism supported by said roof jack mechanism for adjustment in elevation together with said canopy.

46. In a mining machine, the combination with a main frame, of roof jack mechanism 30 on both sides of said frame, a canopy supported on said roof jacks at the roof to span and cover the space above said main frame and extending forwardly from the upper forward end of said frame, and kerf-cutting 35 mechanism also supported by said roof jack mechanism for adjustment in elevation therewith and for operation approximately in the plane of the roof in advance of said canopy.

47. In a mining machine, the combination 40 with a main frame, of means comprising spaced-apart endless traction treads for moving the machine over the mine floor and supporting the same thereon, roof jacks on said main frame to cooperate with said treads to 45 anchor the machine in stationary position, and mining mechanism mounted on the forward end of said main frame in position to operate on an upright mine wall while said frame remains anchored.

50 48. In a mining machine, the combination with a main frame, of transporting means therefor comprising a pair of endless traction treads one on each side of the main frame, roof jack mechanism at the sides of the main 55 frame directly above the respective traction treads to co-operate therewith in anchoring the main frame to hold it stationary, and mining mechanism on the forward end of said main frame in position to operate on an upright mine wall while said main frame is thus anchored in stationary position.

49. In a mining machine, the combination with a supporting frame, of spaced-apart traction treads for said supporting frame, spaced-apart roof jacks one above each of

said traction treads, mining mechanism mounted on said frame for swinging movement relatively thereto on an upright axis, and means for operating said mining mechanism.
